UNITED STATES PATENT OFFICE.

ANKER S. LYHNE, OF BRIDGEPORT, CONNECTICUT.

VANITY BOX.

Application filed July 19, 1923. Serial No. 576,099.

To all whom it may concern:

Be it known that I, ANKER S. LYHNE, a citizen of the United States, residing at Bridgeport, county of Fairfield, State of Connecticut, have invented an Improvement in Vanity Boxes, of which the following is a specification.

This invention relates to vanity boxes, and has for an object to provide a box of this type which will be neat and attractive in appearance, light weight, convenient to use, and will require a small space only in a lady's hand bag or pocket book.

It is a further object of the invention to provide a vanity box which will carry compacts of two different kinds of powder, and will carry them in sealed compartments so that there will be no spilling of the powder and no danger of mixing the two different kinds of powder.

With these and other objects in view I have devised the improved box illustrated in the accompanying drawing, in which—

Fig. 1 is a side elevation of the box closed, 25 a portion of the forward part of the box being shown in section.

Fig. 2 is a front elevation of the box with the cover section raised.

Fig. 3 is a side elevation with the sections 30 as in Fig. 2, a portion of the cover section being broken away.

Fig. 4 is a bottom plan view of the cover section with the interior cover carrying the mirror removed.

Fig. 5 is a side elevation of the box with the various covers in open position, portions being broken away to more clearly show the construction.

Fig. 6 is a partial section through the 40 box on an enlarged scale substantially on the line 6—6 of Fig. 1, and

Fig. 7 is a detailed sectional view showing the method of mounting the inner cover.

The box comprises two cup shaped sections 45 preferably made of thin sheet metal and finished in any desired manner with or without decorations on the outer walls thereof. In the showing in the drawing, the thickness of the various walls is somewhat exaggerated. The two sections of the 50 box comprise the body section 10 and the cover section 11 preferably hinged together by hinge 12, the sections of this hinge being secured to the sections of the box by any

suitable means, but preferably by lugs 13 55 passing through openings in the side walls and bent over on the inner sides as shown in Fig. 4. The upper part of the side wall of the lower section 10 is rolled to provide a flange 14 of somewhat smaller diameter than 60 that of the body of the section, so that it is adapted to telescope within the cover section 11, and also to provide a shoulder 15 to form a stop for the edge of the cover section and to give a smooth continuous and 65 neat appearance to the outer walls of the box when the two sections are closed together.

Otherwise the lower or body section is plain and is adapted to have secured to the 70 bottom thereof, by any suitable means such as cement, a powder compact which comprises usually a metal plate 16 upon the upper wall of which moistened powder is allowed to harden providing a cake of powder 75 secured to the plate as shown at 17. Above this compact is carried the usual puff 18 for applying the powder to the skin. This powder is ordinarily the usual white powder carried in this type of box.

It is very often desirable, however, to carry another kind of powder especially one which has coloring matter, such as rouge, mixed with it, and as the user is often somewhat sensitive about carrying 80 this type of powder it is desirable to have it enclosed in a sealed container which will not open when the box is opened for the use of the ordinary white powder. To provide for this I mount within the cover section 85 a cupped lining 19 which may be secured in the cover section in any suitable manner, but I preferably roll the side walls so as to provide a bead or rim 20 which will snugly fit the inner walls of the sides of the 90 section, and when the lining is forced into this section it will be securely held therein. Preferably in the center of the bottom of the cupped section I form a depression 21 within which is mounted the second powder 100 compact comprising a plate 22 on which is mounted the cake of powder 23. This compact is usually smaller than that carried in the body section as not as much of this powder is used as of the white powder. Around the lower edge of depression 21 I 105 locate an outward and upwardly extending guard 24 preferably substantially crescent

shaped as shown in Fig. 4, and secure it to the cupped lining by any suitable means such as lugs 25 extending through openings in the lining and bent over on the under 5 side thereof. A second puff 26 is carried by this cupped lining and retained therein by the guard 24. This guard will also catch powder which is loosened from the compact by the puff. The side wall of the 10 lining 19, as shown at 27, is somewhat smaller in diameter than the sides of the cover section so that when this lining is inserted in the cover section this side wall will be spaced from the side walls of the 15 cover to allow the entrance of flange 14 on the body section between the lining and cover section. The lining is also provided with an internal bead 28 spaced a suitable distance from the edge thereof upon which 20 the cover 29 may rest when closed.

This cover 29 is a sheet metal cup within which is mounted a mirror 30 and is hinged to the lining 19 by hinge loops 31 and 32 formed integral with the cover and 25 lining and adapted to embrace the hinge pin 33 in the usual manner. The cover 29 fits snugly within the open side of the lining 19 so as to seal the same and prevent powder in the cover section from leaking 30 therefrom either to the body section or when the box is opened. Also, as this cover 29 fits the lining snugly, when the box is opened this cover will be raised with the cover section and all that will be visible 35 will be the white powder and puff, and the mirror 30. If it is desired to use any of the powder carried by the cover section the upper edge of the cover 29 may be drawn forwardly by the lip 34 giving access to 40 the powder and puff carried by this cover section.

I preferably slit the side wall of the cover section as shown at 35 and press a small lug 36 in the body section to extend into 45 this slit when the box is closed to form a catch to secure it in closed position. By pressing inwardly on the front of the side wall of the body section adjacent the lug 36, as shown at 37, the side wall of the body 50 section will be sprung in sufficiently to release this catch and allow the box to open.

It will be apparent from the foregoing that I have provided a box which will carry 55 two different kinds of powder in separate sealed containers or compartments, so that the two kinds of powder will not mix but will always be kept entirely separate. They are also arranged in such manner that the box is compact and so will not require a great deal of space. By spacing 60 the lining from the cover section to allow entrance of the flange 14 between these two elements, I have been enabled to greatly reduce the thickness or height of the box 65 when closed. It will also be apparent that

the various puffs, powder compacts, and the mirror are easily accessible at all times.

Having thus described the nature of my invention, what I claim is:

1. A vanity box comprising cover and body 70 sections adapted for telescoping engagement, one of said sections adapted to carry a powder compact and puff, a cupped lining for the other section spaced from the inner wall of the same at its free edge to allow entrance 75 of the free edge of the other section therebetween, said cupped lining adapted to carry a powder compact and puff, and a cover for closing said cupped lining.

2. A vanity box comprising telescoping 80 body and cover sections, said body section being adapted to receive a powder compact and puff, a cup member mounted within the cover section and provided with a recess to receive a powder compact and puff, a guard 85 extending outwardly from and over the lower edge of said recess, and a cover for closing said cup member and movable therewith when the box is opened.

3. A vanity box comprising hinged body 90 and cover sections adapted for telescoping engagement, said body section adapted to receive a powder compact and puff, a cupped lining secured in the cover section and provided with a recess to receive a powder compact and puff, an outwardly extending 95 guard at one side of said recess, the free edge of said lining being spaced from the inner wall of the cover section to allow entrance of the free edge of the body member 100 therebetween, said lining being provided with an inwardly extending bead around its side wall, a cover hinged to the lining and adapted to rest on said bead to close said cup, and a mirror carried by said cover. 105

4. In a compact container, in combination, a flanged bottom member capable of receiving a powder compact, a flanged top member hingedly attached to the bottom member, a recessed member carried by the top member capable of receiving a powder compact, a mirror-carrying member hingedly attached to the recessed member capable of enclosure within the device in its closed position, said hinge being positioned other than 110 at the hinge between the top member and the bottom member and a mirror carried by the mirror-carrying member. 115

5. In a compact container, in combination, a flanged bottom member capable of receiving 120 a powder compact, a flanged top member hingedly attached to the bottom member, a recessed member carried by the top member capable of receiving a powder compact, a mirror-carrying member hingedly attached 125 to the recessed member capable of enclosure within the device in its closed position and a mirror carried by the mirror-carrying member.

6. A vanity box comprising cover and 130

- body sections adapted for telescoping engagement, one of said sections adapted to carry a powder compact and puff, a cupped member in the other section having an outwardly extending bead around the side thereof below the free edge to engage the side walls of the section to hold the member therein, the free edge of said member being spaced from the side walls of the section 5 sufficiently to allow entrance of the free edge of the other section therebetween, and a cover hinged to said cupped member and fitting within the open side thereof.
7. A vanity box comprising hinged cover and body sections adapted for telescoping engagement, a powder container in one of the sections having side walls spaced from the side walls of the section and arranged to telescope into the side walls of the other 10 section to close the same when the box is closed, and a cover for the container hinged to the container and fitting within the side walls thereof when in closed position.
8. A vanity box comprising hinged cover and body sections, a powder container mounted in one of the sections having side walls arranged to telescope into the side walls of the other section to close the same when the box is closed, and a hinged cover 15 for the container arranged to fit within the side walls thereof when in closed position.
9. A vanity box comprising hinged cover and body sections adapted for telescoping engagement, a powder container in the cover 20 section having side walls spaced from the side walls of the cover section and arranged to fit into the side walls of body section, a hinged cover for the container arranged to
- fit into the side walls thereof when in closed position, and a mirror carried by said cover. 40
10. A vanity box comprising hinged cover and body sections adapted for telescoping engagement, a cupped powder container mounted in the cover section having its side walls at its free edge spaced from the side 45 walls of the cover section to allow entrance of the free edge of the body section and arranged to close said body section when the box is closed, and a hinged cover for the container fitting within the side walls thereof when in closed position. 50
11. A vanity box comprising hinged cover and body sections, a cupped powder container mounted in one of the sections having an external bead in its side walls to engage 55 the side walls of the section and an internal bead inwardly of its free edge, and a hinged cover for said container arranged to fit within the side walls thereof and rest on said internal bead when in closed position. 60
12. A vanity box comprising hinged cover and body sections adapted for telescoping engagement, a cupped powder container mounted in one of the sections having an external bead in its side walls to engage the 65 side walls of the section and to maintain the free edge of the container spaced inwardly from the walls of the section, said container being also provided with an internal bead spaced inwardly from its free 70 edge, and a hinged cover for the container arranged to fit into the side walls thereof and rest on the internal bead.

In testimony whereof I affix my signature.

ANKER S. LYHNE.
